Primary Examiner — Cathron C Brooks*Assistant Examiner* — W. A. Teddy Falloway(57) **CLAIM**

The ornamental design for a plant holder, as shown and described.

DESCRIPTION

FIG. 1 is a perspective view of a plant holder showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of the plant holder in a usage condition.

The broken lines shown in the drawings illustrate environmental structure and form no part of the claimed design.

1 Claim, 5 Drawing Sheets(56)
